GARMENT HANGER

Werdon H. Allen, South Montrose, Pa.

Application June 18, 1938, Serial No. 214,532

3 Claims. (Cl. 223—91)

This invention relates to coat hangers and more particularly to that type of coat hanger having an attachment thereto whereby an additional garment such as a skirt or a pair of trousers may be suspended therefrom.

A primary object of this invention is the provision of an improved auxiliary garment support for a coat hanger whereby an auxiliary garment may be readily and effectively suspended therefrom and readily removed from such suspension if desired.

A further object is the provision of such a support wherein the possibility of disalignment of the parts and consequent weakening of the structure is obviated.

A further specific object is the provision of a coat hanger wherein the trouser or skirt supporting portion is rigidly secured adjacent the ends in the coat hanger whereby twisting or turning of the same is precluded.

A further specific object is the provision of means to prevent any possible interlocking or displacement of the parts comprising the auxiliary garment hanger.

A further object is the provision of a garment hanger which will be simple and inexpensive to manufacture and which will be sturdy and durable and not apt to be rendered inoperative by disarrangement of the parts.

Other objects will in part be obvious and in part pointed out hereinafter.

The invention accordingly consists in the combinations of elements, arrangements of parts and features of construction all as will be more fully pointed out hereinafter and disclosed in the accompanying drawing wherein:

Figure 1 is a side elevational view of one form of this inventive concept,

Figure 2 is an enlarged sectional view taken along the line 2—2 of Figure 1,

Figure 3 is a side elevational view of a modified form of this invention, and

Figure 4 is an enlarged sectional view taken along the line 4—4 of Figure 3.

Similar reference characters refer to similar parts throughout the several views of the drawing.

Having reference now particularly to Figure 1 there is generally indicated at 10 a conventional garment hanger formed of wood or other desired material for supporting a coat. Hanger 10 is provided with a hook 11 whereby the same may be suspended at any suitable location. A pair of wire members 11 and 12 each has an end, 13 and 14 respectively, embedded in and

secured to the under portion of hanger 10. Each of members 11 and 12 is comprised of a downwardly extending portion 15 and 16 respectively and a horizontally extending portion 17 and 18 respectively, at the termination of which horizontal portion is provided with a loop 19 and 20 respectively.

Loops 19 and 20 surround uprights 21 and 22 which comprise portions of a member, generally indicated at 23, which includes a horizontal portion 24 connecting uprights 21 and 22. Uprights 21 and 22 are each embedded in and secured to hanger 10 as indicated at 23 at points adjacent the ends thereof.

Now from the foregoing it will be seen that the member 24 is held in relatively rigid resilient engagement with portions 17 and 18 and that by inserting a garment such as a pair of trousers in the space between members 15 and 16 and subsequently sliding portions of the same outwardly with respect to said space the garment will be held between members 17 and 18 and member 24.

It will also be seen that when it is desired to remove the garment the same may be grasped at the point between members 15 and 16 and readily removed therefrom simply by a direct pull towards the operator when the hanger is in position as indicated in Figure 1.

Having reference now to the form disclosed in Figures 3 and 4 there is generally indicated at 30 a coat hanger of conventional design provided with a hook 31, from which hanger depend two wire members generally indicated at 32 and 33. Member 32 is comprised of a pair of uprights 34 and 35 and a transverse portion 36. Similarly member 33 is comprised of a pair of uprights 36 and 37 and a transverse horizontal portion 38. It will be seen that member 34 engages hanger 30 at a point substantially adjacent its end and that upright 35 engages hanger 30 at a point spaced slightly inwardly from the end. Correspondingly member 37 is secured to hanger 30 exteriorly to member 35 with respect to the adjacent end of hanger 30 and member 36 is spaced inwardly with respect to the opposite end from member 34.

Thus it will be seen that members 38 and 39 lie substantially in the same horizontal plane adjacent each other and, by means of the curvatures of members 34, 35, 36 and 37, as best shown in Figure 4, are resiliently in proximity to each other. Each of members 38 and 39 is provided with a depending projection 40 and 41 respectively which prevent slippage of the transverse

portions 38 and 39 with respect to each other, in such manner as to preclude any possibility of entanglement thereof.

Thus it will be seen that in the event it is desired to use the hanger to support a skirt or analogous article the same may be slipped from either end between members 38 and 39 and held in position by the resilient frictional engagement of these two parts. Similarly due to the fact that both ends of the space between the above mentioned members are open it will be understood that a garment of any desired width, even one having a width greater than the auxiliary supporting device itself, may be readily suspended in the manner previously described.

In the appended claims the terms "horizontal" and "vertical" are used. These terms relate to the position of various members relative to the floor level when the hanger of the instant invention is in suspended relation thereto, or in its normal position of use.

Now from the foregoing it will be seen that there are herein provided two forms of hanger embodying the features of this invention and including many advantages of great practical utility.

As many embodiments may be made of the inventive concept herein shown and described and as many modifications may be made in the embodiments hereinbefore set forth, it is to be understood that all matter hereinbefore described or shown in the accompanying drawing is to be interpreted merely as illustrative and not in a limiting sense.

I claim as my invention:

1. In a garment hanger, in combination, a coat supporting member provided with a hook, a pair of bent wire members, each having one of its ends secured to the underside of said hanger, the said ends of each being adjacent the central portion of said hanger, but being spaced a substantial distance apart, and an additional

member having a horizontal portion of substantial length secured at its ends to said hanger adjacent its extremities, said first mentioned members being secured to said additional member at points adjacent the termination of said horizontal portion to form an additional garment support.

2. In a garment hanger, in combination, a coat supporting member provided with a supporting hook, a pair of spaced apart depending bent wire members, each having an end embedded in the underside of said first mentioned member, one end of each of said wire members terminating adjacent an end of said coat supporting member and the other end of each terminating inwardly from the end thereof, each of said wire members being formed with a portion extending outwardly and substantially horizontally when said hanger is supported by said hook and means resiliently engaging said extending portions to form a supplementary garment supporting device.

3. In a garment hanger, in combination, a coat supporting member, an auxiliary means for holding an additional garment, said means comprising vertically depending and extending wire portions secured in said hanger adjacent a central point thereof but spaced a material distance apart, and extending horizontally a substantial distance towards the ends of said hanger from said vertically extending portions, an additional horizontal member having upturned ends secured to the underside of the coat supporting member said additional horizontally extending member resiliently engaging the horizontal sections of the spaced wire portions and lying in the same horizontal plane whereby a garment may be inserted therebetween and supported thereby and means securing the opposite ends of said horizontally extending portions to points adjacent the ends of said coat supporting member.

WERDON H. ALLEN.
